(57) **CLAIM**

I claim the ornamental design for a combined holder for a drink container and bottle opener, as shown and described.

DESCRIPTION

FIG. 1 is a perspective view of a combined holder for a drink container and bottle opener showing my new design.

FIG. 2 is a front view thereof;

FIG. 3 is a rear view thereof;

FIG. 4 is a side view thereof;

FIG. 5 is a side view thereof from the opposite side to FIG. 4;

(Continued)

FIG. 6 is a top view thereof; and,
 FIG. 7 is a bottom view thereof.
 The broken lines are shown for the purpose of illustrating
 parts of the article that form no part of the claim.

1 Claim, 4 Drawing Sheets
